Felix Moser INVENTOR

UNITED STATES PATENT OFFICE

FELIX MOSER, OF HOLLAND, MICHIGAN

SOUNDING-BOARD BRIDGE FOR PIANOS

Application filed March 25, 1926. Serial No. 97,284.

The invention relates to improvements in soundingboard bridges and fastening them between the soundingboard and the plate. The objects of the improvement are, to provide bridges which will, first, improve the quality of tone by their greater resistance and by eliminating the short lengths of strings between the plate and the old type bridge, second, will simplify construction resulting in greater dependability, third, will reduce cost of production.

The invention consists of the matters herein described and pointed out in claims.

The so-called dead ends of the strings, between the bridge and the hitchpins of the plate, anywhere between 2 and 6 inches long are always a source of mostly undesirable overtones.

This dead end is to be practically eliminated by extending or enlarging the string plate so that it will fully or partly cover the bridge. Plate and bridge will be rigidly fastened to each other. Rigidity being the foremost requirement of a pianobridge to stop and receive the vibration of the usually high tensioned strings at proper string lengths.

The plate thus becomes part of the bridge, furnishing most of that resistance.

In the accompanying drawing, Figures 1—3—5—7 represent four similar cross-sections, showing four types of bridges, all four involving the same acoustic principle, the adaptability of each depending on the construction and direction of the grain of the soundingboard or whether the plate be made of metal or wood, or upon high or low tension of the scale.

Figures 2—4—6—8 represent cross-sections on line 1—1 of Figures 1—3—5—7 respectively, showing the bridges on a line across the strings.

Figures 1—2—3—4 show the bridge in conjunction with a ribbed soundingboard as it is generally used today. The grain of the soundingboard runs in the same direction with the bridge. Figures 5—6—7—8 show the bridge in conjunction with a soundingboard that is not ribbed. The grain of the soundingboard runs crosswise to the bridge.

Figure 9 is a view of the treble side of a

grand piano showing the invention in plan and the manner of securing the stringplate and soundingboard to the frame of the piano.

Figure 10 is a cross-section on line A—A of Figure 9.

In Figures 1 and 2 the bridge 3 is a strip of wood, similar to the kind commonly used. The bridge 3 is rabbeted 4 to allow the plate 5 to fit into it, and is fastened to the soundingboard 6 in the usual way. It is also fastened to the plate (5) by screws 8 or bolts 9. The string 10, stretched over the bridge 3 to the hitchpin 11, imparts its vibrations through the bridge 3 to the soundingboard 6, the ribs 7 acting as conductors of these vibrations to all parts of the board. The bridge may be notched to provide accurate stringlengths and projects above the plate for that purpose. Accurate stringlength may also be obtained by crosswires 12, in which case the bridge 70 may be level with the plate.

Figures 3 and 4 show a sectional bridge 3, consisting of blocks of wood of convenient size and shape, being placed on the soundingboard 6, over the ribs 7, on a line where the bridge should be placed. The sections are fastened to the soundingboard 6 and its ribs 7, and to the plate 5, by means of glue, and screws 8 or bolts 9. The string 10, stretched over the crosswire 12 to the hitchpin 11, imparts its vibrations through the plate 5 and bridge 3, to the soundingboard 6, the ribs 7 acting as conductors of these vibrations to all parts of the board.

In Figures 5 and 6 the bridge 3 is a strip of wood, of the usual lengthwise shape. The bridge 3 is fastened to the soundingboard 6 in the usual way, and to the plate 5, by means of glue, and screws 8 or bolts 9. The string 10, stretched over the crosswire 12, to the hitchpin 11, imparts its vibrations through the plate 5, and the bridge 3, to the soundingboard 6, the bridge 3 acting as conductor of these vibrations to all parts of the board in absence of the ribs.

Figures 7 and 8 show a sectional bridge 3, consisting of blocks of wood of convenient size and shape, being placed on the soundingboard 6 at convenient distances from each other on a line where the bridge should be.

A strip 13 is glued to the other side of the soundingboard 6, on a line corresponding to the sectional bridge 3. Strip 13, soundingboard 6, bridge 3, and plate 5, are fastened by means of glue, and screws 8 or bolts 9. The string 10, passing over the crosswire 12, to the hitchpin 11, imparts its vibrations through the plate 5, and the bridge 3, to the soundingboard 6, the strip 13 acting as conductor of vibrations to all parts of the board in absence of the ribs.

In Figures 9 and 10 the plate (5) is fastened to the frame (14) by screws (15), which run through the blocking or bushings (16), which regulate the height of the string plate, (5) and through the soundingboard (6) which is glued on to the frame (14).

At B a section of the stringplate and soundingboard is broken away to expose the frame (14) of the piano on to which is glued the outer rim (18). For simplicity only one string (10) to the unison is shown. The strings (10) run from the tuning pins (17) over the cross wires or elevations (12) to the hitchpins (11).

A sectional bridge (3) as described in Figures 3 and 4 is shown here. The various sections (3) are fastened between the stringplate (5) and the soundingboard (6) by screws (8) which run into the ribs (7).

The main functions of a soundingboard bridge are: to stop the vibrations of the strings at the proper stringlength and to convey these vibrations to the soundingboard, where they are amplified.

Rigidity or resistance, being the first requirement of a bridge, is acquired by rigidly fastening the bridge between the plate and the soundingboard. Either of the bridges or a combination of them can be used in either upright or grand pianos, the plate being made of metal or wood or whether the soundingboard be ribbed or not.

This specification applies to treble or bass bridges both.

These bridges relieve the immense strain on the soundingboard and its ribs caused by the downward pressure of the strings on the old type bridges. Thus the soundingboard is able to vibrate more freely and naturally. The crowning of the soundingboard which is undesirable becomes unnecessary with these new bridges.

While wood is preferred for this bridge, the use of metal may be resorted to with advantages, mainly in cost of production—namely, the bridge may be cast onto the plate, either sectionally or in full length and fastened to the soundingboard as explained.

I claim:

1. In a stringed musical instrument, the combination of a stringplate with a soundingboard bridge, which is rabbeted to fit the corresponding edge of said stringplate, notched on the opposite edge or having

crosswires for the purpose of terminating the active or live part of the strings and is glued to a soundingboard; extending said stringplate into the rabbet of the bridge and fastening said stringplate to the bridge by screws or bolts.

2. In a stringed musical instrument, the combination of a ribbed soundingboard, a stringplate and a sectional bridge, the sections of the bridge being placed over each rib of the soundingboard respectively, the stringplate having notches, crosswires or elevations for the purpose of terminating the active or live part of the strings and is extended over said sections of the bridge, acoustically and mechanically forming a part of said bridge, the soundingboard, stringplate and the sectional bridge being fastened together by screws or bolts piercing the different sections of the bridge and the ribs of the soundingboard.

3. In a stringed musical instrument, the combination of a bridge which is fastened to a soundingboard, and a stringplate having notches, crosswires or elevations for the purpose of terminating the active or live part of the strings, said stringplate being extended and fastened over the bridge, acoustically and mechanically forming a part of said bridge.

4. In a stringed musical instrument, the combination of an unribbed soundingboard having a strip glued across the grain on its reverse side on a line with the bridge, a stringplate having notches, crosswires or elevations for the purpose of terminating the active or live part of the strings, and a sectional bridge, the respective sections being placed at convenient distance from each other between the stringplate and the soundingboard, said strip and stringplate acoustically and mechanically forming a part of said sectional bridge, being fastened together by screws or bolts piercing the different sections of the bridge and the soundingboard.

5. In a stringed musical instrument, the combination of a soundingboard, a stringplate and a sectional bridge, the respective sections of which are located on the under side of said stringplate at convenient distance from each other and are substantially of the same material the stringplate is made of; said stringplate having notches crosswires or elevations on its upper side for the purpose of terminating the active or live part of the strings, acoustically and mechanically forming a part of said sectional bridge, and is secured to the soundingboard by screws or bolts, which pierce the sections of the bridge.

FELIX MOSER.
